EAR PROTECTOR

Manuel Leaf, Brooklyn, N. Y.

Application February 28, 1940, Serial No. 321,201

5 Claims. (Cl. 132—45)

This invention relates to ear protectors of the type used for protecting the ears of ladies against a blast of hot air used to dry the hair which has been set while wet.

Among the objects of the invention is an ear protector formed of a flat flexible sheet having a curved outer boundary and a separation extending inwardly therefrom, designed to be shipped and stored in flat form, the elements of the sheet adjoining the separation serving as junction elements and embodying retaining means which make it possible to retain them in overlapped relation in which the flat sheet assumes a hollow cup-shaped-like formation and is able to serve as a relatively stiff ear protector which may be readily slipped under the hair over the ear, under the hair net placed on the previously set wet hair without disturbing the hair.

The foregoing and other objects of the invention will be best understood from the following description of exemplifications thereof, reference being had to the accompanying drawing, wherein

Fig. 1 is a view illustrating a hair net held on the head of a lady after the hair has been set, with the ear protectors held under the net over the ears of the user;

Fig. 2 is an outer view of a hollow cup-shaped ear protector exemplifying one form of the invention;

Fig. 3 is a cross-sectional view along line 3—3 of Fig. 2;

Fig. 4 is an elevational view of a flat sheet in the form in which the ear protector of Figs. 2 and 3 is shipped ready for shaping into hollow shape; and

Figs. 5 to 7 are views similar to Figs. 2 to 4 illustrating another form of the invention.

When a lady's hair is set following a hair treatment, such as waving or washing, the hair is shaped and pinned while still wet. Frequently, the wet hair is shaped to overlie the ears, in the form of ringlets, for instance. After the hair has been seen so set and pinned in place, a hair net is usually placed over the head, in the way shown in Fig. 1, so that the blast of hot air used for drying the hair shall not upset the hair. Since such blast of hot air is unpleasant and frequently hurtful to the ears, ear protectors have to be placed over the ears to keep the blast of hot air away from them.

In accordance with the invention, such ear protector is made of a flat flexible sheet having a curved border and two junction elements separated by an inwardly extending separation, the

junction elements being designed to embody means for retaining the junction elements in overlapped relation so as to form out of the sheet a relatively strong hollow cup-shaped-like member which may be readily slipped under the net over the ear of the user without disturbing the overlying hair, while assuring effective protection of the ear canal against blasts of hot air or the like directed against the wet hair. Shallow cup-shaped protectors having a depth of the order of half an inch are desirable for such applications because they may be easily slipped under the net in place over the ear without disturbing any special hair formations, such as ringlets, that overlie the ear.

One form of such protector is shown in Figs. 2 to 4. A flat sheet 10 of flexible material, such as thin cardboard, or cellulosic sheet material, having a curved border, of a symmetrical oval shape, for instance, as shown in Fig. 4, is provided with a separation, such as a cut or slit 11, extending inwardly from one of its boundary portions having a greater curvature. The separation or cut 11 is made long enough and is so arranged that the sheet portions adjoining the separation 11 shall form junction elements 12, 13 by means of which the sheet may be retained in a relatively stiff-cup-shaped formation of substantial strength, shown in Figs. 3 and 4.

As shown in Fig. 4, the junction element 12, which extends in the direction of the longer axis of the overall sheet 10, is slightly shortened at the point where its boundary edge adjoins the separation 11, so that when it is overlapped over the adjoining junction element 13, the cup-shaped ear protector so formed has a substantially even border facing the side of the head adjoining the ear against which the protector is placed. The ear protectors of the invention are designed to be shipped to the users in flat, knocked-down condition, namely, in the form shown in Fig. 4, and to be shaped into the cup-shaped hollow ear protector formation when it is to be put to use. Ready and easy conversion of a flat sheet formation 10 into a cup-shaped ear protector at the place or use is made possible by embodying in the junction elements 12, 13 of the curved flat sheet formation 10 retaining means by means of which the junction elements are readily retained in the cup-shaped formation in which they are used as ear protectors.

As shown in Fig. 4, the retaining means may be embodied in the junction elements 12, 13 by providing one of the junction elements, for instance, the overlapping junction element 12, with

a retaining slit 14, and the adjacent junction element 13, with a cut forming therein a tongue 15 arranged so as to fit into the slit when it is pushed into it while placing the junction elements 12, 13 in overlapped relation, and thereby fixedly retain them in the conical shape shown in Figs. 2 and 3.

To shape out of such flat sheet formation 10, in which form it is shipped, a cup-shaped ear protector shown in Figs. 2 and 3 at the place of use, the operator has merely to place the shorter junction element 12 over the longer junction element 13, push with the finger the tongue 15 through the slit 14 of the overlapping junction element 13, and pull them apart into the interlocked cup-shaped formation.

As shown in Fig. 4, the tongue 15 may be provided near its base with recesses 16 so that when the tongue is pushed into the slit 14, in the way shown in Fig. 4, one of the tongue recesses 16, for instance, the one near the border of the sheet 10, overlaps the adjacent end of the slit 14 thereby strengthening the interlocking connection between the two elements. The retaining slit 14 and the tongue 15, as well as the recess 11, may be embodied in the blank 10 in a single stamping or cutting operation when the blank 10 is cut from a sheet of the material out of which it is made. Accordingly, the provision of the retaining means in the junction elements does not increase the cost of the manufacture of the ear protectors.

Alternatively, the surfaces of the junction elements 12, 13, which face each other when they are brought in overlapped relation, may be joined with a dry adhesive coating provided on one or both of the facing surfaces, the adhesive coating being of a character which remains normally dry and does not form an adhering joint with an adjacent sheet surface against which it is placed without external pressure, but to be energizable to adhere to the adjacent surface when it is pressed against the other surface, for instance, by the pressure of the fingers. Adhesive coating substances of this type are described, for instance, in United States Patents 1,760,320 and 1,895,978.

Alternatively, as shown in Fig. 4, the inwardly facing surface of the junction element 12, bounded by the dotted line 17, and the outwardly facing surface of the junction element 13, bounded by the dotted line 18, may be coated with a dry adhesive compound, for instance, one of the various latex-type adhesive compounds sold by the U. S. Rubber Company as dry seal adhesives or compounds, which when applied in the form of a coating to a surface which is to be united to another surface will form a good union with the other surface only if it is provided with a similar coating, but will generally not adhere to surfaces which do not have such coating. The term "dry seal adhesive coating" as used herein, is intended to designate an adhesive coating which firmly adheres to the sheet to which it is originally applied, but which does not form a firm union with another surface unless such other surface has a similar coating or unless its is firmly pressed against such other surface.

Flat sheet blanks, such as shown in Fig. 4, having such dry adhesive coating on only one of the facing junction surfaces, such as 18, will not adhere to each other when stacked for shipment and storage. Similarly, if both facing surfaces of the junction elements 17, 18 have such dry

adhesive coating which forms a firm adhering junction only to a similar coating, they will likewise not adhere to each other when stacked in the flat form shown in Fig. 4 for shipment, if,

5 prior to stacking, one of the junction elements, for instance, junction element 12, of each flat sheet blank 10, is slightly bent away from its plane, for instance, in outward direction, so as to keep the separations of the flat sheet blanks

10 aligned when they are stacked.

Accordingly, such flat blanks out of which cup-shaped ear protectors are made at the place of use, may be shipped in flat, knocked-down form, thereby facilitating their distribution and storage. In practice, either a tongue-and-slit junction, such as formed by the tongue 15 and slit 14, or a dry seal junction, is sufficient for quickly converting flat sheet blanks 10 of the type shown in Fig. 4 into cup-shaped ear protectors. However, both tongue-and-slit junctions and dry adhesive coatings may be provided on the ear protectors.

Ear protectors of the type shown in Figs. 2 to 4, which may be shipped in flat form, require for 25 shipping and storing only a fraction of the space that would be required for shipping and storing them in their ultimate cup-shaped form. In addition, the manufacturing cost of such ear protectors is reduced without in any way increasing 30 the burden placed on the operator, because the simple operation that has to be performed in forming the cup-shaped protector out of the flat sheet blank 10, is less burdensome than the handling of ear protectors that are shipped and 35 stored in their cup-shaped form.

Other modifications of the invention will suggest themselves to those skilled in the art. In Figs. 5 to 7 is shown another form of an ear protector exemplifying the invention. A substantially circular blank 21 of flexible sheet material 40 has formed therein a pointed tongue-like member 22 by providing in the sheet two converging separations merging into a substantially radial separation slit 23 extending between two junction 45 elements 24, 25. As in the protector of Figs. 2 to 4, the junction elements are provided with interlocking slit and tongue elements 26, 27, similar to the slit and tongue elements 14, 15, respectively, of the ear protector of Figs. 2 to 4.

50 Alternatively, one or both facing surfaces of the junction element indicated by the dotted lines 28, 29 may be coated with a dry adhesive compound for retaining the junction elements 24, 25 in overlapped formation in which the sheet 21 is maintained in a cup-shaped formation 55 shown in Figs. 5 and 6. When the blank 21 is formed into its cup-shaped ear protector structure of Figs. 5 and 6, the tongue-like projection 22 underlies the adjacent edges of the junction 60 elements. The tongue-like member 22 renders the cup-shaped structure formed out of the substantially circular blank 21 somewhat shallower.

Various other modifications of the invention 65 will suggest themselves to those skilled in the art. It is accordingly desired that the appended claims be construed broadly and that they shall not be limited to the specific details shown and described in connection with the exemplifications thereof.

70 I claim:

1. In ear protector means, a flat sheet blank 75 having a curved border and normally retained in its flat formation so as to permit it to be stored and shipped as a part of a stack of similar flat sheet blanks, a separation extending from the

interior of said sheet blank to said border, the portions of said sheet blank having edges adjoining said separation constituting junction elements arranged and designed to embody in the flat condition of said blank retaining means for retaining said junction elements in overlapped relation in which said flat sheet blank is retained in the form of a hollow cup-like member fitting over and protecting the ear of a person against a blast of air or the like, one of said junction elements being cut to form therein a slit and the other of said junction elements being cut to form therein a tongue adapted to be interlockingly inserted into said slit when said junction elements are placed in overlapped relation so as to be retained therein, predetermined portions of each of said junction elements which face each other in their overlapped condition being provided with a pressure-sensitive dry coating adapted to interlockingly retain them in their overlapped relation.

2. In ear protector means, a flat sheet blank having a curved border and normally retained in its flat formation so as to permit it to be stored and shipped as a part of a stack of similar flat sheet blanks, a separation extending from the interior of said sheet blank to said border, the portions of said sheet blank having edges adjoining said separation constituting junction elements arranged and designed to embody in the flat condition of said blank retaining means for retaining said junction elements in overlapped relation in which said flat sheet blank is retained in the form of a hollow cup-like member fitting over and protecting the ear of a person against a blast of air or the like, one of said junction elements being cut to form therein a slit and the other of said junction elements being cut to form therein a tongue adapted to be interlockingly in-

serted into said slit when said junction elements are placed in overlapped relation so as to be retained therein.

3. In ear protector means, a flat sheet blank having a curved border and normally retained in its flat formation so as to permit it to be stored and shipped as a part of a stack of similar flat sheet blanks, a separation extending from the interior of said sheet blank to said border, the portions of said sheet blanks having edges adjoining said separation constituting junction elements arranged and designed to embody in the flat condition of said stack retaining means for retaining said junction elements in overlapped relation in which said flat sheet blank is retained in the form of a hollow cup-like member fitting over and protecting the ear of a person against a blast of air or the like, predetermined portions of each of said junction elements which face each other in their overlapped condition being provided with a pressure-sensitive dry coating adapted to interlockingly retain them in their overlapped relation.

4. An ear protector as defined by claim 3, characterized by the fact that the coated surface portions of said junction elements are so shaped that when said blanks are stacked in their flat condition in alignment with each other the coated portions of one blank will face an uncoated portion of the adjacent blank.

5. An ear protector as defined by claim 1, characterized by the fact that the coated surface portions of said junction elements are so shaped that when said blanks are stacked in their flat condition in alignment with each other the coated portions of one blank will face an uncoated portion of the adjacent blank.
